UNITED STATES PATENT OFFICE

134,947

DESIGN FOR A FOOD TRAY

Reginald V. Stambaugh, Cleveland, Ohio

Application August 26, 1942, Serial No. 108,044

Term of patent 7 years

To all whom it may concern:

Be it known that I, Reginald V. Stambaugh, a citizen of the United States, residing at Cleveland, in the county of Cuyahoga and State of Ohio, have invented a new, original, and ornamental Design for a Food Tray, of which the following is a specification, reference being had to the accompanying drawings, forming part thereof.

In the drawings:

Fig. 1 is a top plan view of a food tray, showing my new design;

Fig. 2 is a front elevational view; and
Fig. 3 is a side elevational view thereof.

Fig. 4 is a sectional view, taken on the line 4—4 of Fig. 1.

Fig. 5 is a rear elevational view of the food tray.

I claim:

The ornamental design for a food tray, as shown.

REGINALD V. STAMBAUGH.
